Primary Examiner — Prabhakar Deshmukh

(74) Attorney, Agent, or Firm — Avyno Law P.C.

(57) **CLAIM**

I claim the ornamental design for a floating target game, as shown and described.

DESCRIPTION

FIG. 1 is a front perspective view of a floating target game showing my new design.

FIG. 2 is a front elevation view of the floating target game of FIG. 1.

FIG. 3 is a rear elevation view of the floating target game of FIG. 1.

FIG. 4 is a side elevation view of the right side of the floating target game of FIG. 1.

FIG. 5 is a side elevation view of the left side of the floating target game of FIG. 1.

FIG. 6 is a top plan of the floating target game of FIG. 1; and, FIG. 7 is a bottom plan of the floating target game of FIG. 1.

1 Claim, 5 Drawing Sheets(56)
